UNITED STATES PATENT OFFICE

JACOB RUPPERT SCHALK, OF RHINEBECK, NEW YORK

RAIL LOCKING MEANS

Application filed March 22, 1928. Serial No. 263,816.

This invention relates to a device for joining together the adjacent ends of rails and locking the same against accidental removal or opening.

The invention is particularly adaptable to rails of boats where one section of a rail is rigidly secured upon posts or stanchions, and a section of the rail is adapted to be either removed or hinged in such a manner as to be opened and folded back upon itself when open.

While the adjacent ends of the stationary and removable rails are provided with securing means, which prevent any movement either downward, sidewise or lengthwise, by a rail securing means which forms the subject matter of a separate invention, there is not any means provided therein for the prevention of opening of the removable section of rail by raising the same, and in some cases this is important.

The object of the present invention is to provide a locking means to prevent accidental opening of the rail securing means.

While this purpose may be accomplished in one of several ways, the logical manner is by a bolt, slidably mounted in one member of the rail securing means, and adapted to enter a hole provided in the other member, to prevent their removal, one from the other; and some suitable means for operating said bolt.

Another object of the invention is to provide means for this purpose that shall be simple, durable, contain few parts and be easy of operation and positive in its action.

With these and other objects in view, my invention consists in certain construction and combination of parts as will hereinafter be fully described and claimed, and illustrated in the accompanying drawings, which form a part hereof and in which like figures of reference refer to corresponding parts in all of the views, but it is fully understood that slight changes may be made without departing from the spirit of the invention.

In the drawings:

Figure 1. is a top plan view of a rail locking device embodying my invention.

Figure 2. is a sectional view of the same

taken on the line A—A of Figure 1. to show the details of construction.

Figure 3. is an end view of the female portion, showing the abutting end.

Figure 4. is an end view of the male portion, showing the rail holding end.

Figure 5. is an end view of the same, showing the abutting end.

Figure 6. is a sectional view similar to Figure 2. showing a modified method of operating the locking bolt.

Figure 7. shows a bottom plan view of the same.

Figure 8. shows an end view of the same.

Referring to the drawings:

The device comprises the two interlocking rail end members 10 and 11, adapted to be secured upon the adjacent ends of stationary and movable rail sections, by securing the ends of said rail sections within the recessed ends 12 of said members, in some suitable manner such as pinning or by screws or bolts.

The member 10 is designated as the female member, and is formed with the female part of a dovetail 13; while the member 11 is the male part, and is formed with the male portion of a dovetail 14, interlocking with the part 13.

It is to be understood that the members 10 and 11, may be of any desired shape in cross section, and of any suitable material.

Referring to Figures, 2, 3, 4 and 5, within the male member 11, is mounted a sliding bolt 15, which may be round square or flat as desired, and which is slidably mounted in the dovetail 14, and a vertical web 16, both provided with aligned holes.

With said member 11, and slidably mounted in a slot 17 formed in the bottom thereof, is a block 18, which is formed with a hole 90 through which the bolt 15 is passed, and therein held by a screw 19 threaded therein with its point engaging said bolt 15; and between said block 18 and the web 16 is placed a spiral spring 20 on the bolt 15 to retain it in 95 the normal closed position as shown.

The forward end of the bolt 15 is formed with a beveled striker 21, which as the members are being closed will contact with the upper edge of the dovetail 13 and force 100

the bolt back against the action of the spring 20.

For operating the bolt 15, there is provided a finger piece 22, which slides on the lower surface of the member 11 and is secured to the block 18 by the screw 19, so that by a pull on said finger piece 22 the bolt 15 will be withdrawn from engagement with the member 10.

In the construction shown in Figures 6, 7 and 8, the bolt 15 is mounted in the dovetail 14 and a lug 24 formed on the member 11, which have alined holes therein; and a spiral spring 20 is placed on said bolt 15 between said dovetail 14 and the lug 24; a pin 25 being placed in said bolt 15 to engage the end of the spring 20, to retain said bolt 15 in the normal position as shown.

For operating said bolt 15 against the action of the spring 20, the bolt 15 near its rear end is formed with a vertical slot 26, within which is mounted the arm 27 of a bell crank which is pivoted in a bifurcated lug 28 formed on the bottom of the member 11; said crank, having an arm 29 provided with a button 30 extending through a hole 31 in the bottom of the member 11 in such a manner that by pressing said button 30 the bell crank will draw back the bolt 15.

It is understood that the button 30 may project beyond the member 11, or be flush with its surface, or be in a depression in the same as desired, or it may be on the side instead of on the bottom.

It is also to be understood that the locking bolt 15 may be operated in place of the two methods shown, by a knob, which by the turning of the same will withdraw the bolt, or a key may be used for the same purpose if desired.

Having thus described my invention, what I claim as new and desire to secure by Letters Patent, is.

In a marine hinged guard rail locking device, and in combination with two engaging rail members formed with recessed ends for attachment to the adjacent ends of the guard rail, one of said members formed with a dove-tail slot adapted to engage with a dove-tail lug on the other member to form a joint between said members, a lug formed within the recess of one member, a bolt slidably mounted therein and in the end of said member and engaging the end of the other member, a spring mounted on said bolt between said lug and the end of the member to retain said bolt in a locked position, and a releasing finger operated means secured to said bolt for withdrawing the same.

In testimony whereof I affix my signature.

JACOB RUPPERT SCHALK.
